INTEGRATED CIRCUIT SOCKET

Richard J. Hanlon and Herbert G. Yeo, Attleboro, Mass., and Richard M. Grubb, Cumberland, R.I., assignors to Augat, Inc., Attleboro, Mass., a corporation of Massachusetts

Filed Jan. 23, 1967, Ser. No. 5,512

Term of patent 14 years

(Cl. D26—1)

FIG. 1

FIG. 2

FIG. 3

FIG. 4

FIG. 5

FIG. 6

FIG. 7

FIG. 1 is a top perspective view of an integrated circuit socket, showing our new design;

FIG. 2 is a bottom perspective view thereof;

FIG. 3 is a bottom plan view thereof with the broken lines omitted for convenience of illustration;

FIG. 4 is a top plan view thereof;

FIG. 5 is an end elevational view thereof, looking from the left with respect to FIG. 1;

FIG. 6 is a side elevational view thereof; and

FIG. 7 is an end elevational view, looking from the right with respect to FIG. 1.

The dominant features of our design reside in the full-line portions of the drawing.

We claim:

The ornamental design for an integrated circuit socket, substantially as shown and described.
